UNITED STATES PATENT OFFICE.

FRANZ KRUCKENBERG AND WILLY BLACK, OF HEIDELBERG, GERMANY; SAID BLACK
ASSIGNOR TO SAID KRUCKENBERG.

HIGH-SPEED SUSPENDED RAILWAY.

Application filed April 27, 1928, Serial No 273,317, and in Germany November 25, 1926.

This invention relates to streamline vehicles for high-speed suspended electric railways; more especially it relates to a buffer-arrangement for the same.

- 5 The provision of buffers for high speed suspended mono-railways has to be designed from quite a different point of view from that for usual railways. While usual rail vehicles can follow one another with either end, and 10 must therefore be provided with buffers at both ends, monorail suspended railways can only hang in one direction owing to the carrier arm extending over the rail from one side. Consequently a front end can only follow a 15 back end, or a back end follow a front end, and two similar ends can never be adjacent. For this reason it suffices to provide the buffer or buffers at only one end, in all the vehicles therefore only at the front or at the back.
- 20 A further important consideration in the design of the buffer is the speed at which the vehicle travels. At the speeds contemplated the air resistance is of extreme importance. Now, for example, a single locomotive buffer 25 of about 400 mm. diameter, exposed freely to the air stream, has the same air resistance as a streamline body of about 1600 mm. diameter which corresponds approximately to an aeroplane fuselage of usual size with an ideal 30 streamline form. From this example it is clear that a high speed vehicle correctly designed to give the lowest possible air resistance cannot have buffers of the usual kind built on to or into it.
- 35 Novel buffers and buffer arrangements are described below, in which all the conditions of their application have been taken into account.

- 40 The invention is illustrated diagrammatically and by way of example on the accompanying drawings on which Figure 1 is a front-view (drawn to a very small scale) of a high-speed suspended electric railway vehicle of the type for which our invention is intended; Figure 2 is a side-view of that suspended vehicle, and Figure 3 a similar representation showing a modification of the same; Figures 4 and 5 axial sections through the adjacent ends of two adjacent vehicles, of which one is provided with our improved 45 buffer arrangement, these figures being drawn to a greatly enlarged scale relatively to Figs. 1-3 and the vehicles being supposed to be axle-

driven; Figure 6 is an axial section through only one vehicle which is to be driven by a 55 propeller, the buffer arrangement being combined with the propeller shaft, and Figures 7, 8 and 9 show further modifications which are all fully described hereinafter.

Figures 4 and 5 of the accompanying drawings, show the buffer arrangement for axle driven vehicles. Only a single buffer is used, mounted at the rear end, while the front end is correspondingly strengthened to take shocks. In order to cause no, or as little as possible, additional air resistance, the shock receiving device is built into the streamline vehicle body except for a length equal to the shock stroke. The buffer itself can be provided in the usual way with conical, helical, 60 ring or other springs. In order not to damage the front wall of the adjacent vehicle, the buffer head 1 is advantageously provided with a covering 2 of rubber or similar material. For the same reason, the front wall may also 65 have a shock absorbing cover 3 of the same material. The shock pressure is taken by longitudinal bearers 4, 5, 6, 7 and 8 and transferred to the framework. These longitudinal bearers are jointed by a member 9 which at 70 one end carries the buffer, at the other the shock receiving, strengthened, front wall.

75 The features of a streamline body, namely blunt at the front and pointed at the rear and the further difficulty that monorail suspended vehicles can swing, so that the contact point of the buffer is not so closely confined as in usual railway vehicles, but diverges more or less from the centre line according to the amount of swing, necessitate of themselves 80 that the buffer be located at the rear and that a receiving surface of as large size as possible be provided at the front.

85 It is more difficult to arrange the buffering when the vehicle is propeller driven (Figure 95 3 of the accompanying drawing). There are various possibilities. Several basic methods are more closely described below.

90 Figure 6 of the accompanying drawings shows an arrangement with the buffer on the propeller hub. The propeller 10, shown in this case as a wooden propeller, is secured in the usual way on a shaft 13 by means of flanges 11 and 12. A mounting 14 is bolted 100 to the hub together with the flanges 11 and 12. To this mounting, after the propeller

has been threaded upon or otherwise secured to the shaft, the actual buffer is secured and held to the rim 15 by screws. The buffer is a rubber ball filled with air under pressure and 5 consists of a pneumatic type of a cover 16 of strong rubbered linen, and a bladder 17 of soft rubber. The plate 18 on which the ball is mounted corresponds to the rim of a motor car wheel. The ball can be filled, 10 when mounted, with air under pressure through a valve 19. The cone 20 through the nut 21 presses the bead of the outer ball into the rim and thus prevents its coming out under side blows. The inflated ball can naturally 15 be replaced by a similar one of sponge or solid rubber or similar material, but the first has the advantage that its energy capacity for shocks can be altered as desired by regulating the air pressure and it can be suited to the weight of the vehicle. A guided 20 buffer of light construction can also be used instead of the ball. In all such arrangements, as in Figure 7, the shocks coming on to the propeller hub are transmitted from the shaft 25 to the longitudinal carrier by a thrust bearing placed as closely as possible behind the hub.

In the arrangement of Figure 7 a hollow propeller shaft 22 is used as the buffer guide. The buffer head 23 abuts against a helical or 30 ring spring 24 carried in the propeller shaft. The buffer head 23 may for example be retained in the shaft by the propeller nut 25 and the spring at the same time preloaded. The shock is again transmitted from the propeller shaft through a thrust bearing 26 to the longitudinal bearers 27 and 28 of the vehicle. A sheet metal ring 29 secured by screws to the propeller and into which the buffer 23 enters, as indicated by the chain 35 lines, when shocks occur, is provided to maintain the streamline form of the vehicle.

Figure 9 shows a shock absorbing arrangement in which on the occurrence of shocks the propeller shaft itself slides axially and 40 so acts as the buffer guide. The propeller is secured on the shaft in the usual way. The propeller shaft 30 is borne in a bearing piston 32 sliding in a body 31. At any suitable point between the propeller and motor shaft 45 any usual axially sliding coupling, for example a splined coupling 33, is provided. The buffer spring 34 which can be in the form of a helical, conical or ring spring abuts at one end against the bearing piston 32, at the other 50 and against the body 31 and transmits the shocks through this body to the longitudinal bearers 36 and 37. A safety distance 38 provided additionally to the maximum stroke 55 completely protects all vital mechanical parts, particularly the driving gear and motor, from any damage through excessive shocks. The preloading of the buffer spring 60 is greater than the highest propeller thrust to prevent floating movements to and fro of 65 the propeller shaft. To maintain the stream-

line course of the vehicle contour the propeller hub is provided with a ring 39 in extension of the vehicle shell, which ring moves into the vehicle as indicated by the chain lines when a shock occurs. The hub is here also 70 provided with a shock absorbing covering 40 of rubber or similar material, which can be secured to the hub by the aid of an embedded metal ring 41 and extended hub bolts 42.

With a large driving vehicle or two coupled vehicles (Figure 3) with two driving propellers, the front hub advantageously has a similar shock absorbing covering to the rear hub (Figure 8).

We claim:

1. In a vehicle having a body of streamline contour, a shock-absorbing element arranged at the end of said body and of a shape to conform to the streamline contour of the body.

2. In a vehicle having a body of streamline contour, a shock-absorbing device arranged at the end of said body and of an external contour conforming substantially to the streamline contour of the body.

3. In a vehicle for high-speed suspension railways, a body of streamline contour, and a shock-absorbing element arranged at the end of said body and of a shape substantially conforming to the streamline contour of the body.

4. A vehicle of a type adapted to be arranged in trains, including a body of streamline contour having a front end and a rear end, said body being provided at its rear end with a shock-absorbing element of a shape substantially conforming to the streamline contour of the body and compressible to absorb shocks, the front end of said body being provided with a buffer member against which the shock absorbing element of the preceding vehicle in a train may strike.

5. In a vehicle having a body of streamline contour, a shock-absorbing device arranged at one end thereof and of a shape to substantially conform to the streamline contour of the body, said shock-absorbing device including a resilient compression member to accommodate movement of the device axially of the body, the other end of said body provided with a buffer member rigidly mounted thereon.

6. In a vehicle for high-speed suspension railways, a body of streamline contour, an air propeller mounted at the end of said body, and means for absorbing shocks of impact of said body, said means including a shock absorbing member of streamline contour to substantially conform to the streamline contour of the body, said shock absorbing member being carried by and rotatable with said propeller.

7. In a vehicle for high-speed suspension railways, a body of streamline contour, an air propeller mounted at the end of said body,

means for imparting rotation to said propeller including a driving shaft, and means for absorbing shocks of impact of said body, said means including a shock absorbing member of streamline contour to substantially conform to the streamline contour of the body, said shock absorbing member being rotatable

with said propeller and movable axially relatively to said driving shaft upon the occurrence of impact.

In testimony whereof we affix our signatures.

FRANZ KRUCKENBERG.

WILLY BLACK.
